DESIGN FOR A BRAID

Herman Stern, New York, N. Y.

Application October 7, 1948, Serial No. 149,001

Term of patent 7 years

(Cl. D3—32)

To all whom it may concern:

Be it known that I, Herman Stern, a citizen of the United States and a resident of New York city, county and State of New York, have invented a new, original, and ornamental Design for a Braid, of which the following is a specification, reference being had to the accompanying drawing, forming part thereof.

The figure is a plan view of a piece of braid showing my new design.

The broken lines outline a design unit, which unit is repeated throughout the length of the braid as indicated.

The drawing is lined to indicate color contrasts.

I claim:

The ornamental design for a braid, substantially as shown and described.

HERMAN STERN.
